INTERNAL COMBUSTION ENGINE

Albert Heess, Stuttgart-Bad-Cannstatt, Germany, assignor to Daimler-Benz Aktiengesellschaft, Stuttgart-Unterturkheim, Germany

Application July 28, 1937, Serial No. 156,083
In Germany August 1, 1936

8 Claims. (Cl. 123—117)

My invention relates to an internal combustion engine cooperating with a compressor and, especially to an improved control of the ignition of the engine, and is particularly applicable to motor vehicles.

When an internal combustion engine, for instance an engine of the carburetor type, cooperates with a compressor, the timing of the ignition must be adjusted in dependence of the operating condition of the compressor. If the compressor is inactive, the ignition must be advanced compared with the requirement existing when the compressor is active and supplies the engine with a precompressed combustion medium. When the engine has been operating with the compressor being inactive and when it is desired to start the compressor, it is necessary that the operator retard the timing of the ignition at the same time. Inversely, when the compressor has been working and when it is desired to continue the operation of the engine without pre-compression, the operator must advance the timing of the ignition in order to secure a proper operation of the engine.

It is a primary object of my invention to provide a safeguard that the timing of the ignition will be changed automatically coincidentally with a change in the operating condition of the compressor so as to render the ignition control fool-proof. This is particularly important for motor vehicles as it will relieve the driver of the necessity of paying attention to a re-adjustment of the ignition every time he starts or stops the compressor.

However, the invention is not limited to motor vehicles but is broadly applicable to the control of the ignition system of any internal combustion engine cooperating with a compressor.

A further object of my invention is to provide means whereby the timing of the ignition may be controlled by hand but will be retarded, irrespective of its manual setting, when the compressor is put in operation, and will be re-set to advanced position again when the compressor is disabled.

I attain these and other objects by subjecting the ignition device to the control from a member controlled in its turn by the compressor. Preferably, however, the ignition timing device is subjected to the dual control from two elements, one of which is manually settable, while the other one is pneumatically operable by the compressor in such a manner that the ignition is automatically retarded, as the pressure produced by the compressor increases.

Further objects of my invention will appear from the description of a preferred embodiment described hereinafter, and the features of novelty are pointed out in the claims.

In the drawing:

Fig. 1 is an elevation of the steering device of a motor vehicle equipped with a pneumatic member and a hand lever for jointly controlling the ignition;

Fig. 2 is a slightly modified enlarged view of the lower part of Fig. 1, partly in section; and

Fig. 3 is a side view of the mechanism shown in the left lower part of Fig. 2.

21 denotes the chassis of a motor vehicle equipped with an internal combustion engine 15 20 of the carburetor type, and with a compressor 19 which is driven by the engine 20 and adapted to feed pre-compressed air to the carburetor or a pre-compressed fuel mixture to the intake manifold of the engine. The hollow steering shaft 20 4 bearing the steering wheel 1 is journaled in the housing 5 which encloses the steering gear and is mounted on the chassis 21 in the conventional manner. A manually settable element, e. g. a lever 2, is fixed to the upper end of a rod 25 3 extending from the steering wheel 1 downwardly through the hollow steering shaft 4 and carrying a disk 6 at its lower end. This disk is provided with a ball stud 7 connected by a linkage with an element for timing the ignition of the 30 engine which may be a swingable arm 18 of a distributor 17 which forms part of the ignition system. The arm 18 is swingable between a right-hand advanced position and a left-hand retarded position.

Thus, the operator may adjust the ignition to meet the requirements depending on the speed of operation, the temperature of the engine, the nature of the fuel and other factors, as is well known in the art. The compressor 19 may be 40 rendered active or inactive during the operation of the engine at the driver's option by manipulation of a suitable controlling member not shown. To ensure that the ignition be automatically retarded when the compressor is started and be 45 advanced when the compressor is cut off, I have provided a member controlled by the compressor which is connected with the movable element 18.

This member is preferably in form of a pneumatic member movable in response to the pressure produced by the compressor. In the embodiment shown, this pneumatic member is formed by a piston 12 slidably guided within a cylinder 13 which is mounted on the housing 5. One end of the cylinder is connected with the 55

atmosphere by a bore 22 while the other end is connected with the compression chamber or discharge port of the compressor 19 by a suitable conduit, for instance by a pipe indicated at 15. 5 A helical spring 23 inserted between the cover of the cylinder and the piston 12 tends to shift the same towards the right and to keep it in contact with an adjustable stop screw 24. It is apparent that when the compressor is put in operation, compressed air will enter the chamber 13a of the cylinder through the pipe 15 and will act on the piston 12 moving the same towards the left against the pressure of the spring 23.

The manually adjustable element 2 and the member 12 controlled by the compressor jointly control the ignition timing element 18. To this end, numerous cooperative connections between the three elements or members 2, 12 and 18 may be used. I prefer, however, to use a particularly 20 simple arrangement which I will now describe.

The linkage connecting the ball stud 7 with the swingable arm 18 comprises a link 9 hinged to the ball stud 7 and by a pivot 25 to the arm 10 of a two-armed lever, the other arm 10a of 25 which is connected with the arm 18 by a link 16.

The lever 10, 10a is mounted on a movable support connected to the pneumatic member 12. In the embodiment shown, this support is formed by piston rod 11 connected to the piston 12 and 30 slidably in the cover of the cylinder 13. The end of the piston rod 11 carries a stud engaging a slot provided in the lever 10, 10a between its ends.

The operation is as follows:

35 The driver may retard the ignition by turning the hand lever 2 moving the rod 16 in the direction of the arrow b, or may advance the ignition by turning the hand lever in the opposite direction, swinging arm 18 towards the right, as the rod 3 will transmit the rotation of the hand lever 2 to the disk 6 thus transmitting the movement through the linkage 9, 10, 10a, 16 to the arm 18 of the distributor. In this manner, the driver may adjust the ignition of the engine 40 to meet the existing requirements. When the compressor is put in operation moving the piston rod 11 towards the left, the lever 10, 10a will swing about the pivot 25, irrespective of the position the pivot 25 may have at that time. The resulting movement of the link 16 in the direction of the arrow b will retard the ignition.

45 When the compressor is cut off, the spring 23 will return the piston 12 towards the right to its initial position and this will cause the linkage 10, 10a, 16 to advance the ignition again. 50

55 The spring 23 may be so chosen that the piston 12 will move into its outermost left position, whenever the compressor operates, irrespective of the pressure produced by the compressor, or it may be so dimensioned as to move towards the left in proportion to the pressure produced by the compressor. In the latter alternative, the ignition will be continuously retarded as the pressure produced by the compressor increases.

60 While I have selected a mechanical linkage 9, 10, 10a, 11, 16 to interconnect the elements for timing the ignition, the member controlled by the compressor and the manually settable element, it will be readily understood that my invention is not limited thereto, as means other than mechanical means may be used for establishing such a cooperative connection. Also, the ignition system may include further adjusting means in addition to those described hereinabove, for instance the customary automatic 65

means adjusting the ignition in dependence of the speed of operation of the engine.

70 My invention is not limited to the exact details of the construction shown but includes such variations and modifications as come within the scope of the appended claims.

What I claim is:

1. The combination comprising an internal combustion engine, a compressor cooperating therewith, an element for timing the ignition of said engine movable between an advanced position and a retarded position, a manually adjustable element connected with said first-mentioned element for manual control of the ignition, a member controlled by said compressor, and means connecting said member with said movable element and adapted to displace the latter towards its retarded position, when said compressor is active, irrespective of the position of said manually adjustable element. 20

2. The combination comprising an internal combustion engine, a compressor cooperating therewith, an element for timing the ignition of said engine movable between an advanced position and a retarded position, a manually adjustable element, a connection between said elements for setting the ignition by hand, and a member controlled by said compressor cooperating with said connection and adapted, when said compressor is active, to cause said connection to displace said movable element towards its retarded position irrespective of the position of said manually adjustable element. 25

3. The combination comprising an internal combustion engine, a compressor cooperating therewith, a distributor having an arm for timing the ignition of said engine swingable between an advanced position and a retarded position, a hand lever, a linkage connecting said hand lever with said arm, and a pneumatic member controlled by said compressor and responsive to the pressure produced thereby, an element included in said linkage being connected with said pneumatic member and adapted to move said arm to its retarded position irrespective of the setting of said hand lever, as the pressure produced by said compressor increases. 40

4. In a motor-driven vehicle, the combination comprising an internal combustion engine, a compressor cooperating therewith, a distributor having an arm for timing the ignition of said engine swingable between an advanced position and a retarded position, a hollow steering shaft, a hand lever mounted adjacent to the upper end thereof, a rod connected to said hand lever and extending through said shaft, a linkage connecting the lower end of said rod with said arm for manual control of the ignition, a housing surrounding the lower end of said hollow steering shaft, a cylinder mounted on said housing, a conduit connecting said cylinder with said compressor, a piston slidably in said cylinder in response to the pressure produced by said compressor, and a connection between said piston and said linkage adapted to cause the latter to move said arm towards its retarded position, when said pressure increases, irrespective of the position of said hand lever. 55

5. The combination comprising an internal combustion engine, a compressor cooperating therewith, an element for timing the ignition of said engine movable between an advanced position and a retarded position, a manually adjustable element, a connection between said elements for manual control of the ignition, a lever 70

75

included in said connection, a movable support carrying said lever, and pneumatic means responsive to the pressure produced by said compressor and connected with said support to move the same in a sense retarding the ignition, when said pressure increases.

5 6. The combination comprising an internal combustion engine, a compressor cooperating therewith and adapted to be rendered active or inactive, an element for timing the ignition of said engine movable between an advanced and a retarded position, two controlling members connected with said element for joint control thereof, and means causing one of said controlling members, when said compressor is rendered active, to displace said movable element towards its retarded position.

10 7. In an internal combustion engine, in combination, an ignition timing device for said en-

gine movable between advanced and retarded positions, manually operated means for controlling said device, said means being connected to said device through a linkage system including a double-arm lever, one end of which is connected to the manually operated means and the other end to said device, a pivot for said lever at the intersection of its two arms, means for supplying fluid under pressure to said engine, and means responsive to the pressure of said supplied fluid for varying said pivot, whereby said ignition device is automatically controlled irrespective of the position of said manual means.

15 8. The combination according to claim 7 in which said automatic means includes a piston, and a connecting rod attached at one end to said piston, the end of said connecting rod forming the pivot for said double-arm lever.

15 ALBERT HEESS.
